US0D1071460S

(12) **United States Design Patent** (10) Patent No.: **US D1,071,460 S**
(45) Date of Patent: ** Apr. 15, 2025

(54) **DRYING MAT**

(71) Applicant: **Hills Point Industries, LLC**, Westport, CT (US)

(72) Inventors: **Jennifer Richter Bernstein**, Westport, CT (US); **Phuong Hoang**, Stamford, CT (US)

(73) Assignee: **Hills Point Industries, LLC**, Westport, CT (US)

(**) Term: **15 Years**

(21) Appl. No.: **29/840,051**

(22) Filed: **May 25, 2022**

(51) LOC (15) Cl. **07-05**

(52) U.S. Cl.

USPC **D32/55; D32/57**

(58) **Field of Classification Search**

USPC **D32/55-59**

(57) **CLAIM**

The ornamental design for the drying mat, as shown and described.

DESCRIPTION

FIG. 1 is a top perspective view of the drying mat.

FIG. 2 is a front view of the drying mat, with the rear view being the same.

FIG. 3 is a right side view of the drying mat, with the left side view being the same.

FIG. 4 is a plan view of the drying mat; and,

FIG. 5 is a bottom view of the drying mat.

The broken lines in the drawings form no part of the claimed design.

1 Claim, 5 Drawing Sheets
